[57] CLAIM

The ornamental design for a disposable swab applicator package with standby reservoir, substantially as shown and described.

DESCRIPTION

FIG. 1 is a perspective view of a disposable swab applicator package with standby reservoir; showing my new design;

FIG. 2 is a left-side plan view thereof;

FIG. 3 is a typical end view thereof;

FIG. 4 is a bottom plan view thereof; and

FIG. 5 is a perspective view of my disposable swab applicator package with standby reservoir, but shown when in use.

FIG. 1

FIG. 2

FIG. 3

FIG. 4

FIG. 5
